W. THOMPSON

NUT LOCK

Filed August 29, 1925

Patented Apr. 27, 1926.

1,582,193

UNITED STATES PATENT OFFICE.

WALTER THOMPSON, OF AIRDRIE, ALBERTA, CANADA.

NUT LOCK.

Application filed August 29, 1925. Serial No. 53,322.

To all whom it may concern:

Be it known that I, WALTER THOMPSON, a citizen of the United States, residing at Airdrie, in the Province of Alberta and Dominion of Canada, have invented certain new and useful Improvements in Nut Locks, of which the following is a specification, reference being had to the accompanying drawings.

10 This invention relates to certain improvements in nut locks and has relation more particularly to a device of this general character especially designed and adapted for use in holding against displacement the nuts comprised in a rail joint, and it is an object of the invention to provide a device of this kind and a novel and improved means whereby the same may be readily and conveniently applied in working position.

20 Another object of the invention is to provide a novel and improved device of this general character consisting of a member adapted to be arranged alongside of a fish plate and to engage the nuts associated therewith together with means engageable with the rail for maintaining the device in applied position.

It is also an object of the invention to provide a novel and improved device of this general character which, after being arranged in applied position, is spiked or otherwise secured to the ties of a trackway to maintain the device in applied or working position.

35 The invention consists in the details of construction and in the combination and arrangement of the several parts of my improved nut lock whereby certain important advantages are attained and the device rendered simpler, less expensive and otherwise more convenient and advantageous for use, as will be hereinafter more fully set forth.

The novel features of my invention will hereinafter be definitely claimed.

45 In order that my invention may be the better understood, I will now proceed to describe the same with reference to the accompanying drawings, wherein:

50 Figure 1 is a fragmentary view in elevation illustrating a nut lock constructed in accordance with an embodiment of my invention and in applied position;

Figure 2 is a view in top plan of the structure as illustrated in Figure 1;

55 Figure 3 is a sectional view taken substantially on the line 3—3 of Figure 1;

Figure 4 is a view in perspective of my improved nut lock unapplied.

As disclosed in the accompanying drawings, R denotes the meeting ends of rails 60 with each side of which is associated in a well-known manner the fish plate 1 and with which coact in a conventional manner the holding bolts 2 and nuts 3.

The purpose of the invention is to provide 65 means for holding the nuts 3 against displacement and as herein set forth said device comprises an elongated plate 4 adapted to be disposed along the fish plate 1, said plate 4 being of a length greater than the 70 length of the plate 1 to extend beyond opposite ends thereof.

The opposite end portions of the plate 4 at the lower margin thereof are provided with the outstanding flanges 5 adapted to 75 have close contact with the adjacent base flanges 6 of the rails R. Each of the flanges 5 is continued by an inwardly disposed curved or arcuate member or arm 8 adapted to be disposed beneath a rail with its free end substantially flush with the opposite side of the base of the rail when the device is in applied position. The free end portion of the member or arm 8 is flattened, as at 9, and said flattened portion is provided with a slot 10.

A U-shaped member 11 is adapted to straddle the flattened portion 9 and the adjacent base flange of the rail R, the lower or under arm a of said member 11 adjacent its outer end is provided with a lug or rib 12 which engages within the slot 10 when said member 11 is forced inwardly of the rail R to working position.

As the member 11 is forced into applied 95 position the curved arms or members 8 as they are correspondingly sprung inwardly toward the bottom of the rail will operate to maintain the plate 4 effectively in applied position. The flanges 5 are also continued by the wings 14 each of which being adapted to contact with a tie from above and with which it is adapted to be operatively engaged by a spike or the like to further maintain the locking device in working position.

The plate 4 has its lower marginal portion cut out to provide a plurality of open slots 15, the lower portion c of each of the slots being of greater width than the upper portion. By this arrangement the plate 4 may be caused to straddle the nuts 3 from above irrespective of the position of the side faces

of said nuts and whereby such nuts 3 will be effectively locked against backward movement or displacement.

From the foregoing description it is thought to be obvious that a nut lock constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:—

20 1. A nut lock for rail joints comprising an elongated plate provided with open slots to receive the nuts when the plate is in ap-

plied position, arms carried by the plate and extending below the rails when the plate is in applied position, each of said arms being 25 provided with a slot in its outer end portion, and a U-shaped member engageable with the outer end portion of each of said arms and the adjacent portion of a rail, said member being provided with a lug engaging 30 within the slot of the arm.

2. A nut lock for rail joints comprising an elongated plate provided with open slots to receive the nuts when the plate is in applied position, arms carried by the plate and extending below the rails when the plate is in applied position, and a U-shaped member engageable with the outer end portion of each of said arms and the adjacent portion of a rail. 35 40

In testimony whereof I hereunto affix my signature.

WALTER THOMPSON.
